US00D970720S

(12) **United States Design Patent** (10) Patent No.: **US D970,720 S**
Gordon et al. (45) Date of Patent: **** Nov. 22, 2022**

(54) **FRAME OF A NASAL MASK**(71) Applicant: **Fisher & Paykel Healthcare Limited**,
Auckland (NZ)(72) Inventors: **Callum Ross Gordon**, Auckland (NZ);
Ryan Anthony Graham, Auckland (NZ);
Bruno Sintive, Auckland (NZ);
Mark Andrew Thompson, Auckland (NZ);
Amit Galgali, Auckland (NZ);
Vicky Dan Gao, Auckland (NZ);
Cameron Robert Willis, Auckland (NZ);
Jake Baker Hocking, Auckland (NZ);
Priyanka Ferdinand Pereira,
Auckland (NZ)(73) Assignee: **Fisher & Paykel Healthcare Limited**,
Auckland (NZ)(**) Term: **15 Years**(21) Appl. No.: **29/695,955**(22) Filed: **Jun. 24, 2019****Related U.S. Application Data**

(62) Division of application No. 29/618,347, filed on Sep. 20, 2017, now Pat. No. Des. 855,793.

(51) LOC (13) Cl. **29-02**

(52) U.S. Cl.

USPC ..... **D24/110.4**(58) **Field of Classification Search**USPC D24/110, 110.1, 110.4-110.6, 127

(57) **CLAIM**

The ornamental design for a frame of a nasal mask, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front and side perspective view of a first embodiment of a frame of a nasal mask embodying our new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof, and

FIG. 8 is a top, front and side perspective view of a second embodiment of a frame of a nasal mask embodying our new design;

FIG. 9 is a front view thereof;

FIG. 10 is a rear view thereof;

FIG. 11 is a first side view thereof;

FIG. 12 is a second side view thereof;

FIG. 13 is a top view thereof; and,

FIG. 14 is a bottom view thereof.

In the second embodiment of a frame of a nasal mask, the illustrated blue color is a claimed feature of our design.

UNITED STATES PATENT AND TRADEMARK OFFICE
CERTIFICATE OF CORRECTION

PATENT NO. : D970,720 S
APPLICATION NO. : 29/695955
DATED : November 22, 2022
INVENTOR(S) : Callum Ross Gordon et al.

Page 1 of 17

It is certified that error appears in the above-identified patent and that said Letters Patent is hereby corrected as shown below:

On the Title Page

Replace title page, page 3 as shown with the attached replacement title page, page 3.

On page 3, in the description, insert the following text on a line between the description of FIG. 7 and FIG. 8. --FIG. 8 is a cross sectional view on a centerline of the frame;--; Replace the text “FIG. 8” with --FIG. 9--; Replace the text “FIG. 9” with --FIG. 10--; Replace the text “FIG. 10” with --FIG. 11--; Replace the text “FIG. 11” with --FIG. 12--; Replace the text “FIG. 12” with --FIG. 13--; Replace the text “FIG. 13” with --FIG. 14--; Replace the text “FIG. 14” with --FIG. 15--.

In the Drawings

Replace drawing sheets 1-14, and on the title page, the illustrative print figures (FIGS. 1 and 8), as shown with the attached replacement drawings sheets 1-15.

Signed and Sealed this
Nineteenth Day of September, 2023

(57) CLAIM

The ornamental design for a frame of a nasal mask, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front and side perspective view of a first embodiment of a frame of a nasal mask embodying our new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof, and

FIG. 8 is a top, front and side perspective view of a second embodiment of a frame of a nasal mask embodying our new design;

FIG. 9 is a front view thereof;

FIG. 10 is a rear view thereof;

FIG. 11 is a first side view thereof;

FIG. 12 is a second side view thereof;

FIG. 13 is a top view thereof; and,

FIG. 14 is a bottom view thereof.

In the second embodiment of a frame of a nasal mask, the illustrated blue color is a claimed feature of our design.
